UNITED STATES PATENT OFFICE

2,251,467

CARPET SWEEPER

John W. Scott and Fred W. Pullen, Grand Rapids,
Mich., assignors to Bissell Carpet Sweeper Co.,
Grand Rapids, Mich.

Application August 5, 1939, Serial No. 288,560

7 Claims. (Cl. 306—11)

This invention relates to improvements in carpet sweepers.

This invention relates to carpet sweepers and particularly to the means for yieldingly holding the handle of the sweeper in vertical position when the sweeper is not in use.

Heretofore various means have been provided to accomplish this purpose. One of the commonest means consisted of a plate having projecting nibs engageable with the handle of the sweeper as it was moved to or from vertical position. The metal employed in making the handle of the sweeper and the nibs was ordinarily relatively soft so that as soon as the initial coat of oil on the parts wore off, the parts began to wear and the wear continued so that in a very short time the nibs became ineffective.

The objects of this invention are:

First, to provide a new and improved nibbing construction for carpet sweepers.

Second, to provide such a construction which obviates the above difficulties.

Third, to provide such a structure in which anti-friction means are provided to eliminate or greatly reduce friction between the nibs and bail in a carpet sweeper.

Fourth, to provide such a construction which is inexpensive and highly effective.

Further objects and advantages pertaining to details and economies of construction and operation will appear from the description to follow. Preferred embodiments of our invention are illustrated in the accompanying drawing, in which:

Fig. 1 is an end view of a carpet sweeper embodying our invention.

Fig. 2 is a detail view of the nib plate and arm of the bail in the sweeper shown in Fig. 1 with the bail in raised position.

Fig. 3 is a detail sectional view on the line 3—3 of Fig. 2.

Fig. 4 is a plan view of a blank employed in forming the anti-friction means in the sweeper shown in Figs. 1-3.

Fig. 5 is a view similar to Fig. 3, showing a different type of anti-friction means used in carrying out our invention.

The carpet sweeper 1 has the usual case 2, wheels 3 and brush 4. The handle 5 has the usual bail 6 with bail arms 7 pivoted to the ends 8 of the case with pivot nibs 9.

At 10 we show a nib plate which has nibs 11 projecting therefrom into the path of movement of the bail as it is moved to or from vertical position. These nibs are located one on each side of the bail when it is in vertical position and

serve to hold the bail in vertical position. In the particular form of invention shown, the bail is slightly resilient and is able to slide over the nibs because of this as the handle is moved to or from vertical position. The actual movement is shown in dotted lines in Fig. 3.

On the arm 7 of the bail and retained on the portion of the bail which moves past the nibs 11 is a sleeve 12 which embraces and is rotatably mounted on the arm. This sleeve consists of a strip of metal 13 having one end recessed at 14 and the other end formed at 15 to provide interengaging means. After the ring is moved on the bail arm 7, means 16 are provided by deforming the metal of the bail to retain the sleeve in position to engage the nibs. It will be apparent that when the bail is swung to or from vertical position, the sleeve 12 will rotate as the nibs engage it so as to materially reduce friction and wear, thus assuring a proper supporting of the handle in vertical position for a considerable period of time during the use of the carpet sweeper. The particular form of sleeve with the interengaging means 14 and 15 has proven quite effective because there is no tendency for the sleeve to open up at the seam during use.

In Fig. 5, we show a modified form of the invention. The plate 110 is provided with recesses 11 on either side of the bail arm 107 when it is in vertical position. These recesses are apertured at 118 and balls 111 are confined behind the plate 110 and between the end of the case and the plate. The balls are free to rotate and project through the openings 118 sufficiently to engage the bail as it moves to or from vertical position. Upon engagement of the bail with the balls, the balls rotate, thus eliminating friction. If desired, the balls may rest directly against the end of the case or may have a wear plate 119 therebehind.

It will be apparent that this arrangement of parts is simply and easily installed and that it may be produced at a minimum of expense.

We have shown two forms of our invention, but it will be apparent that other forms of invention could be made and we do not wish to be limited to the two specific forms shown. We have defined the invention in the claims.

Having thus described our invention, what we claim as new and desire to secure by Letters Patent is:

1. In a carpet sweeper having a case and a handle with a bail having its arms pivotally engaging the ends of the case, bail engaging nibs projecting from the end of the case on opposite

sides of an arm of the bail when it is in vertical position, a sleeve rotatably mounted on and embracing said arm of the bail, said sleeve comprising a strip of metal wrapped around said arm and having its ends formed with interlocking means thereon, and means holding said sleeve in position to engage said nibs as the bail is moved to or from vertical position, whereby said sleeve rotates on said arm as the nibs are engaged.

2. In a carpet sweeper having a case and a handle with a bail having its arms pivotally engaging the ends of the case, bail engaging nibs projecting from the end of the case on opposite sides of an arm of the bail when it is in vertical position, a sleeve rotatably mounted on and embracing said arm of the bail, and means holding said sleeve in position to engage said nibs as the bail is moved to or from vertical position, whereby said sleeve rotates on said arm as the nibs are engaged.

3. In a carpet sweeper, the combination of a pivoted handle, nibs located in the path of movement of the handle as it is moved to or from vertical position and engageable therewith, and a sleeve rotatably mounted on said handle, and means for holding said sleeve in position to engage said nibs as the handle is moved to or from vertical position.

4. In a carpet sweeper, the combination of a pivoted handle, nib means engaging said handle as it is moved to or from vertical position and to hold said handle in vertical position, said handle and nib means including anti-friction rotatable ball means operable as antifriction bearing means between said handle and nib

means upon engagement of the handle and nib means during movement of the handle to reduce friction.

5. In a carpet sweeper having a case, and a handle with a bail having its arms pivotally engaging the ends of the case, a nib plate on the end of the case between the bail and the case when the bail is in vertical position and having recesses on opposite sides of the bail when it is in vertical position, each recess being apertured, and a ball in each recess projecting through said aperture sufficiently to engage the arm of the bail when it is pivotally moved on the sweeper.

6. In a carpet sweeper having a case and a handle with a bail having its arms pivotally engaging the ends of the case, bail engaging nibs projecting from the end of the case on opposite sides of an arm of the bail when it is in vertical position, said nibs each comprising a ball projecting from the end of the case to engage the bail as it is moved to or from vertical position, and means confining said balls on the end of the case in such a manner as to permit rotation of the balls when engaged by the arm of the bail upon movement thereof.

7. In a carpet sweeper, the combination of a pivoted handle, and a pair of nibs projecting into the path of movement of the handle on opposite sides thereof when the handle is in vertical position, comprising a pair of balls and means for holding said balls in position while permitting rotation thereof upon engagement with said handle in its movement to or from vertical position.
